UNITED STATES PATENT OFFICE.

LEO J. GRUBMAN, OF NEW YORK, N. Y., ASSIGNOR TO VOICES, INCORPORATED, OF NEWARK, NEW JERSEY, A CORPORATION OF DELAWARE.

METHOD AND MEANS FOR CONNECTING A FLEXIBLE BODY WALL TO A BELLows HEAD.

Application filed February 7, 1924. Serial No. 691,102.

This invention relates to an improved method and means for connecting a flexible body wall to a bellows head.

My present improvements have more particular relation to that type of bellows which has come into very general use in recent years in connection with sound producing devices for dolls and other toys and wherein the bellows is usually of cylindrical form and has a flexible body wall suitably fixed at one of its ends and connected at its other end to a movable air expelling head. Heretofore the end of the flexible bellows wall has been connected to the movable head either by the use of a suitable adhesive or by means of a clamping ring whereby the end of the tubular wall is held in connection with the head by a frictional clamping pressure. Such connecting or attaching means has not, however, been found entirely satisfactory in practical use, first because of the liability of air leakage, which is particularly true when an adhesive connection is employed, secondly, because of the difficulty of assembling, and thirdly, in the case of the frictional clamping ring because of the added expense of production involved in the use of such additional part for effecting the connection.

It is the primary purpose of this invention to provide a simple and easily and quickly operable method and a very effective means for securely and permanently fixing the end edge of the tubular bellows wall in connection with the bellows head whereby the possible escape of air under pressure from the interior of the bellows chamber will be absolutely precluded and whereby the end edge of the flexible wall becomes inseparably united with the bellows head. Thus, notwithstanding the most severe strains upon the flexible wall incident to the operation of the device there will be no separation of the end edge of said flexible wall from the bellows head. In a preferred embodiment of the invention, I provide the bellows head which is formed of a suitable malleable metal with a flange against which the end edge of the flexible wall is positioned. This flange is then subjected to pressure by means of a suitable tool whereby the flange is compressed upon and against the edge of said flexible wall so that the latter is immovably clamped and held be-

tween said compressed flange and the body portion of the bellows head. 55

With the above and other objects in view, the invention consists in the improved method and means for connecting the flexible wall to the bellows head as will be hereinafter more fully described in detail, illustrated 60 in the accompanying drawing and subsequently incorporated in the subjoined claims.

In the drawing in which I have illustrated several different forms of the bellows head which may be employed in carrying out my 65 present improvements,

Figure 1 is a vertical sectional view showing the bellows head positioned within one end of the tubular flexible wall prior to the die pressing operation; 70

Figure 2 is a similar view showing the condition of the parts after the completion of the die pressing operation whereby the flexible wall becomes permanently attached or secured to the bellows head; 75

Figures 3 and 4 are fragmentary sectional views similar to Figures 1 and 2 illustrating a slightly different form of the bellows head; and

Figures 5 and 6 are fragmentary views 80 corresponding to Figures 3 and 4 respectively, illustrating still another modification.

In the drawing for purposes of illustration, I have shown a cylindrical bellows head 85 5 which is provided with a central axially extending sleeve 6 extending from the face of said head. The wall of this sleeve is adapted to coact with a sound emission member (not shown). However, it 90 will be understood that the manner of controlling the emission of sound in the operation of the device in which the bellows may be incorporated, constitutes no essential part of the present invention, and the 95 bellows head 5 may be of various other constructions than that illustrated in the drawing. For the purpose of this explanation, it will suffice to state that regardless of the form and construction of this head, said 100 head is provided with an annular flange 7 in concentric relation to the periphery thereof. As shown in Figure 1 of the drawing, normally this flange 7 projects laterally from one face of the bellows head 5 and in 105 suitably spaced relation to its peripheral

face. The head 5, I prefer to cast or form from lead, or other suitable malleable metal alloy or composition material.

The body wall 8 of the bellows is composed of a suitable flexible semi-elastic material which is capable of withstanding very severe tensile strains without tearing or rupture. One end of this flexible tubular bellows wall 8 is suitably fixed to one end of a casing or shell within which the bellows and other operating parts of the device are enclosed, but since this attaching means is of no importance in so far as the present disclosure is concerned, it is not herein described or illustrated. The tubular flexible wall 8 at its other end is normally of somewhat less diameter than the diameter of the bellows head 5. In assembling the parts, the flexible tubular wall 8 is drawn over the bellows head until said head is positioned in one end of the tubular body wall, whereby said flexible wall is laterally distended or expanded so that the annular end portion of said wall has a very tight hugging frictional fit upon the peripheral face of the bellows head, the end edge portion of said flexible wall extending inwardly over one side of said head and against the outer side of the flange 7 as shown at 9.

After the bellows head has been thus positioned in one end of the tubular wall 8, said head is arranged upon an anvil 10 having the centering pin or post 11 to extend loosely through the central opening or sleeve 6 of the head. A die member 12 is now forced downwardly under pressure upon the bellows head, said member being provided in its bottom face with an annular channel or groove 13. The flange 7 first engages with the inner side of the wall of this groove and as the downward pressure of the die 12 continues, the said flange is then turned outwardly and over the end edge portion 9 of the tubular bellows wall 8. In this outward bending or turning of the annular flange 7, the metal thereof is also subjected to a compressing action by the die 12 and the extreme edge portion of the flexible bellows wall is turned over upon itself between this compressed flange and the marginal body portion of the head 5. From reference to Figure 2 it will therefore be seen that the end edge portion of the flexible bellows wall is practically incorporated or combined with the structure of the head 5, thus precluding all possibility of separation of the parts and also effectually preventing the leakage of air from the bellows chamber between said flexible wall and the bellows head. In sounding devices of the type wherein the bellows head moves by gravity to effect the expulsion of air from the bellows chamber and its re-inflation, the pull or strain upon the attached end of the flexible body wall of the bellows is very se-

vere. This is particularly true when the doll within which the sounding device is incorporated is roughly handled to cause a rapid gravity movement of the bellows head which is suddenly limited or abruptly stopped by the expansion of the flexible wall 8. In such cases, the separate frictional clamping ring engaged upon the marginal portion of the bellows head is not altogether effective and is quite likely to be loosened or displaced so that the flexible bellows wall may become detached from the movable head or loosened to such an extent that there will be a considerable leakage of air from the bellows chamber. Not only is my present method and means for securing the flexible wall in connection with a movable bellows head more effective and reliable but it is likewise obvious that since I entirely dispense with the use of an additional or separate part such as the frictional clamping ring, I am enabled to appreciably decrease the cost of production.

While I prefer to secure the flexible bellows wall to the head by means of a flange 7 such as is shown in Figures 1 and 2 of the drawing, it is evident that there are various alternatives for this bendable or compressible securing flange on the bellows head which might be employed. Thus in Figure 3 of the drawing, I show the bellows head 5 provided with the outer marginal annular flange 14 and with a second inner annular flange 7'. These flanges are spaced apart to provide the annular groove 15. After the tubular bellows wall has been drawn over the head 5 as above explained the end edge portion of said wall is turned around the flange 14 and against the inner face of said flange within the groove 15. By means of a suitable die pressure is then applied against the inner side of the flange 7' and said flange is forced outwardly under pressure and against the end edge of the flexible bellows wall, thereby completely closing the groove 15 and permanently confining the end edge of the flexible wall between the flange 7' and the flange 14.

In Figure 5 of the drawing I have shown another form of the bellows head, in which case, said head is provided in one side thereof and adjacent its periphery with an annular channel or groove 15', thus forming the marginal circumferential flange 14' thereon. The tubular bellows wall 8 is turned over this flange 14' against the inner face thereof as in Figure 3 of the drawing. By means of a suitably formed die, pressure is now applied in an inward direction against the outer side of the flange 14' and upon the flexible bellows wall engaged thereover. Thus, as seen in Fig. 6 of the drawing, this flange is forced inwardly so that the end edge of the bellows wall will be permanently clamped and held between the inner face of

said flange and the inner side wall of the groove 15' which is opposed thereto. Either of these alternative methods will produce a satisfactory connection which may be very quickly made at small expense of time and labor and for obvious reasons is preferable to the use of a separate clamping or attaching element.

From the foregoing description considered in connection with the accompanying drawing, my improved method and the several mechanical means whereby the same may be satisfactorily practiced will be clearly and fully understood. By means of my present improvements, in the manufacture of sounding devices which have become known in the art as "voices" for talking dolls or other toys, the assemblage of the several parts entering into the construction of the bellows whereby air is expelled under pressure through the sounding reed is very greatly expedited. At the same time, however, it will be appreciated that my invention does not sacrifice security and permanency of the connection between the parts to speed. Thus by reason of the fact that I have succeeded in reducing time, material and labor costs in the production of such devices, an article of this kind superior to those heretofore known in the art can be profitably manufactured and sold at less cost to the consuming public than the devices of the prior art.

I have herein illustrated and described several satisfactory and practical embodiments of my present invention. Nevertheless it will be understood that the essential features thereof might also be exemplified in other constructions and I accordingly reserve the privilege of resorting to all such legitimate changes in the form and arrangement of the several detail parts as may be fairly considered within the spirit and scope of the invention as claimed.

I claim:

1. The method of connecting a flexible tubular bellows wall to a head which consists in providing the head with a part yieldable under pressure, then arranging said head and said part within one end of said tubular wall and then compressing said yieldable part of the head upon the end edge of said wall to effect a permanent connection and air tight seal between said flexible wall and the head.

2. The method of connecting a flexible tubular bellows wall to a head which consists in providing a head with an annular flange yieldable under pressure, then arranging said head within one end of said tubular wall, and then subjecting said annular flange to the pressure of a tool to displace said flange from its normal position and force the same under a uniformly applied pressure upon the end edge of said tubular wall to confine the edge of said tubular wall between

said flange and a part of the head and thereby effect a permanent connection and air tight seal between said flexible wall and the head.

3. The method of connecting a flexible 70 tubular bellows wall to a head having a part 75 yieldable under pressure which consists in forming said head of greater diameter than one end of said tubular wall and drawing the tubular wall over said head to position the head within said end of the tubular wall and thereby distend said end portion of the tubular wall beyond its normal diameter, and then subjecting said yieldable part of the head to pressure and thereby causing said 80 yieldable part of the head to permanently confine the end edge of the tubular flexible wall between said part and an opposed surface of the head.

4. The method of connecting a flexible 85 tubular bellows wall to a head which consists in forming the head of malleable material and providing the same with an annular 90 flange inwardly spaced from the periphery of said head, then drawing the tubular flexible wall over said head to position the same within one end of said tubular wall with the end edge thereof extending inwardly and against said annular flange, and then subjecting said annular flange to the pressure of a tool to thereby turn said flange outwardly upon the marginal portion of 95 said head and fold the end edge of the tubular wall upon itself whereby said folded edge of the tubular wall is permanently confined between the marginal face of said head and said flange.

5. In combination, a tubular bellows wall of flexible material, a gravity movable operating head for said bellows enclosed by 105 one end of said tubular wall, and said head having an integral annular part exerting a uniform frictional confining pressure upon the end edge of said tubular wall to effect a permanent air tight connection between said 110 tubular wall and the head.

6. In combination, a tubular flexible bellows wall, a head of slightly greater diameter than one end of said tubular wall, said head being engaged within said end of the 115 tubular wall and distending said wall beyond its normal diameter, said head being provided with an annular non-expanding flange extending upon the end edge of the tubular wall and frictionally confining the same against a surface of said head to thereby effect a permanent air tight connection between said tubular wall and the head.

7. In combination, a flexible tubular bellows wall, a gravity movable operating head 125 for collapsing and distending said bellows wall, one end of the tubular wall surrounding said head, and said head having a part of malleable material adapted to be displaced under pressure and engaged upon the end 130

edge of said tubular wall to permanently confine the latter between said part and a surface of said head and thereby effect an air tight connection between the tubular bellows wall and said head.

8. In combination, a tubular flexible bellows wall, a head for one end of the bellows formed of malleable material and of greater diameter than said end of the tubular wall, said end of the tubular wall surrounding said head and being distended thereby, and an integral annular flange on said head forced under pressure upon the end edge of said tubular wall to frictionally and permanently confine said end edge of the wall between said flange and a surface of the head and thereby effect an air tight connection between said tubular bellows wall and the head.
9. In combination, a tubular flexible bellows wall, a head for one end of the tubular bellows wall, said end of the tubular wall surrounding said head and being dis-

tended thereby, said bellows head having an integral annular flange spaced from the periphery of the head and forced outwardly under pressure over and upon the end edge of said tubular wall whereby the latter is permanently confined between said outwardly turned flange and one side face of the bellows head to thereby effect an air tight connection between said tubular bellows wall and the head.

10. In a bellows, a tubular collapsible body wall, a weighty head for collapsing and distending said tubular bellows wall, said head having a surface to be engaged by the end edge of said wall, and a non-resilient part carried by said head and adapted to be displaced under pressure upon said edge of the tubular bellows wall to frictionally clamp and permanently confine the same against said surface.

In testimony that I claim the foregoing as my invention I have signed my name hereto.

LEO J. GRUBMAN.
